(57) **CLAIM**

The ornamental design for the belt worn controller as shown and described.

DESCRIPTION

FIG. 1 is a front perspective view of the belt worn controller showing our new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines immediately adjacent to the shaded areas depict the bounds of the claimed design, while all other broken lines are directed to environment. The broken lines form no part of the claimed design.

The “Viomerse” lettering and icon forming part of the disclosure is a registered trademark of Viomerse, Inc.

1 Claim, 7 Drawing Sheets
